PUNCHING MACHINE

Herman J. Klotz, Endicott, N.Y., assignor to International Business Machines Corporation, New York, N.Y., a corporation of New York

Original application August 27, 1953, Serial No. 376,929, now Patent No. 2,789,819, dated April 23, 1957. Divided and this application June 14, 1956, Serial No. 591,391

3 Claims. (Cl. 164—115)

This invention relates generally to record making devices and more specifically to a punched card reproducer operated under control of a punched document.

This application is a division of the application in the name of H. J. Klotz, Serial No. 376,929, filed August 27, 1953, now Patent No. 2,789,819. In the present application, the disclosure and claims are directed to the improved combination of a ticket feeding and sensing device and a record card punching machine.

The invention is illustrated in connection with merchandise control work in which a relatively small price tag stub is prepunched with basic merchandise information and forms the original document which is sensed to control the perforation of standard "IBM" type accounting machine cards. It is the main object of the present invention to provide a device which will accept the tag stubs and convert them into the standard control records.

Another object of the present invention is the provision of a novel ticket feeding and sensing device and record card punching machine combination wherein in a single machine cycle a ticket is fed out of the hopper, sensed and ejected into a stacker while the corresponding record card which is to be punched is fed only to the entrance of the punch mechanism. In prior art punching machines the master cards and detail cards feed along in synchronism each taking about four machine cycles to feed through the machine for reproducing and gang punching. In the present combination, each ticket is reproduced on the cycle after it has ejected. This is advantageous in applications where the reproduced card is checked at the punch brushes and the machine stopped when an error occurs because when the error is detected at the punch brushes the ticket in question will already have been ejected into the stacker. Consequently, the machine can be immediately restarted without having to search for and remove the ticket in question from some part of the feed mechanism proper.

Another object of the present invention is the provision of a novel feed mechanism for feeding the ticket stubs to the reproducing machine.

A further object of the present invention is the provision of a novel arrangement for stacking said stubs in a feed hopper with means for offsetting the bottommost stub so that the registration holes therein may be properly positioned for feeding of the stub to the reproducer sensing mechanism.

A further object of the invention is to provide a novel pin feeding mechanism for engaging the registration holes in each stub as the stub is offset from the remainder of the stack and to successively feed the stubs to the sensing mechanism.

Another object of the present invention is to provide an improved sensing mechanism which is conveniently attached to the stub feeding mechanism and which is adapted to statically sense small code holes pierced in the ticket stubs.

2

Still another object of the present invention is to provide the reproducer with a simple translator circuit for converting the code punchings on the ticket stubs into a standard control record code. In the present embodiment the code used on the price tags is a five element, consistent two out of five code having bit values of 1, 2, 4, 7 and check.

Other objects of the invention will be pointed out in the following description and claims and illustrated in the accompanying drawings, which disclose, by way of example, the principle of the invention and best mode, which has been contemplated, of applying that principle.

In the drawings:

Fig. 1 is a side elevation view of the ticket stub feeding and sensing devices shown attached to the frame of the reproducing machine.

Fig. 2 is a plan view taken on line 2—2 of Fig. 1.

Fig. 3 is a side elevation taken on line 3—3 of Fig. 2 showing the driving connections between the ticket stub feeding and sensing devices and the reproducing machine. The side frame of the machine has been removed for clarity.

Fig. 4 is a plan view in partial section with the sensing device removed.

Fig. 5 is a sectional view taken on line 5—5 of Fig. 4 showing various cam drive connections.

Fig. 6 is a perspective view showing the components of the skid roll drive mechanism and the eject mechanism along with a partial showing of the sliding block pin feed mechanism.

Fig. 7 is a detail view of the card lever mechanism for controlling operation of the pin feed device.

Fig. 8 is a detail view showing the relationship between the bottom two tickets in the ticket magazine prior to feeding.

Fig. 18 is a sectional elevation view of the reproducing machine showing the feeding, sensing and perforating devices.

Fig. 19 is a chart showing the code relays of the relay storage device.

Figs. 20a to 20c comprise a wiring diagram.

Fig. 21 is a timing flow chart of three cycles of operation of the ticket feeding and sensing devices.

Price tag

Referring to Fig. 16, there may be seen a typical merchandise tag consisting of a ticket portion T and a stub portion S. Both the ticket and the stub are proportioned with a plurality of punched information index point positions there being 24 vertical columns of 5 punching positions each along with a 25th column of 2 punching positions. There are, then, a possible 122 index point positions, such as indicated at H, at which information may be prepunched into the ticket or the stub.

Arranged horizontally across the top of the ticket and

the stub is printed information relating to the size and price of the particular article to which the tag will be attached. Columns 10 through 12 are reserved for punchings relating to the size of the article and columns 20 through 24 for punchings relating to the price. The word "size" preceding the size field and the dollar sign and the decimal point shown in the price field would be preprinted on the tag by the tag manufacturer. All of the punchings and remaining printed matter is put on the tag by a tag marking machine prior to attaching the tag to the merchandise. The tag marking machine forms no part of the present invention and hence will not be described.

Across the bottom of the ticket and the stub is a horizontal row of printed coded information relating to such items as manufacturer, color, style, etc. The printing is offset vertically into actually two rows to indicate the different fields of information. The punchings in columns 1 through 9 and 14 through 19 relate to said bottom rows of printed information, this information being printed also by the tag marking machine prior to attaching the tag to the article.

The two punchings indicated as H' in column 25 are control punchings used to control the operation of the punching machine in a manner to be described.

The code used for punching the necessary information into the ticket and the stub is shown in Fig. 15. The code used is a well-known 5 element, consistent 2 out of 5 code having the bit values of 1, 2, 4, 7 and check. As will be understood later, the columns on the tag which, in the illustrative example, are to be reproduced on an IBM card (columns 1 through 24) must have 2 and only 2 punchings in each column in order to carry out the reproducing operation.

The tag marking machine in addition to putting the above-described information on the tag also prepunches a series of three feed registration holes indicated at F and F' on the ticket and stub shown in Fig. 16. As will be described, the registration hole F serves to position the stub in the feed hopper and to aid in properly feeding the stub out of the hopper. The registration holes F' are used to feed the stub to the sensing mechanism where the punchings H and H' are sensed to control the reproducing machine. In addition to the registration holes there is also prepunched in each ticket a hole indicated at A on Fig. 16. The hole A is used to attach the tag to the article of merchandise by means of a string or the like.

Each stub has a semicircular notch N cut at one end which is used to aid the clerks in stacking the stubs as the merchandise is sold. At each sales station there is a stacker box into which the tag stubs are placed as the sales are made. The stubs are detached from the tag and the ticket portion remains with the article and serves as the customer's record of sale. Each stacker box is provided with a suitable guide bar which intercepts the notch N in the stubs and insures that the stubs will be properly stacked for use in the feed hopper of the ticket stub feeding device. As will be presently understood the ticket stub feeding device and sensing mechanism is attached to the read side of the well-known IBM reproducing punch and during the converting operation actually functions in place of the read unit of the machine.

Before describing the application of the novel ticket stub feeding device and sensing mechanism to the reproducing punch it is thought advisable to briefly describe the construction and operation of the standard punching machine illustrated in the embodiment of the present invention.

Punching machine

The high-speed reproducing punching machine is constructed according to the principles set forth in Patent Re. 21,133 issued to C. D. Lake on June 27, 1939, and is shown in Figs. 17 and 18. Reference may be had to this patent for a full and comprehensive understanding of the various machine parts and functions thereof, as

well as of the operation of the device as a whole. Briefly, however, and for the purpose of illustration, during normal operation of the machine a number of master cards 10 (Fig. 18) are contained in a hopper R and an additional group of blank record or detail cards 11 are contained in a hopper P. The cards are fed singly and concurrently from both hoppers and are then shifted in synchronism through sensing and punching stations before being deposited in stackers 12 and 13.

- 10 Upon leaving the hopper R, each master card 10 first encounters a master sensing brush 14, then a line of sensing brushes 15, and finally a series of checking brushes 16. The detail cards 11 upon leaving the hopper P each pass a master sensing brush 17, then a line of punches 18 and finally a set of checking brushes 19. The brush 14 cooperates with a special perforation in the original or master card 10 and when such a perforation is sensed a class selection operation may take place to shift the sensed data to a selected field on the record or detail card. The brush 17 is used for field selection of gang punching and also for control of suspension of master card feeding when the machine is conditioned for combined gang punching and reproducing.

Electrical connections exist between the line of brushes 15 and the line of punches 18 so that when a perforation is sensed in a master card 10, a perforation is punched in the related detail card 11 in a corresponding position. After the cards have passed the first sensing and punching stations respectively, they enter separate checking stations. In these stations the master card 10 is sensed by the checking brushes 16 at the same time that the related detail card is sensed by the checking brushes 19. If the perforations in both cards do not agree, the machine is stopped and a lamp or other signal indicates the error.

- 25 Referring now to Figs. 17 and 18 wherein the driving connections of the machine are shown, a motor M is mounted above the base 20 of the machine which also carries a pair of main side frames 21. The motor is connected by a driving belt 23 to a pulley 24 on a shaft 25 suitably mounted in bearings in the frames 21. Fixed to the shaft 25 is a gear 26 which serves to drive all of the continuously running instrumentalities of the machine. Suitable gearing designated in its entirety at 30 extends between the driving gear 26 and a relatively large punch clutch driving gear 27 which is pivoted on a punch feed drive shaft 31 and attached to another driving gear 32. Gear connections are provided between the punch clutch under the hopper P and another clutch under the hopper R so that cards may be fed in synchronism from 35 both hoppers. The gear 32 meshes with another gear 33 pivoted as at 34. This gear 33 in turn meshes with a similar gear 35 pivoted as at 36. The gear 35 meshes with a reproducer clutch driving gear 37 mounted on a shaft 38. The gear 37 meshes with a gear 39 secured to a shaft 40 and thus this latter shaft is given a continuous movement. It serves as a mounting for a number of cams cooperating with a series of cam contacts C1, C2, etc., hereinafter referred to, and also as a mounting for an impulse distributor wheel 28 shown in Fig. 20b and which constitutes an actuating device for a pair of contacts C11, the function of which will be set forth fully hereinafter.

40 The gear 37 (Fig. 17) has secured thereto a clutch disc 42 provided with a notch 44. Cooperating with the notch 44 is a pawl 46 mounted on an arm 48 attached to the shaft 38. One end of the pawl is engaged by an armature latch 50 and the other end of the pawl is formed with an extension 52 adapted to fall into the notch 44. A suitable spring (not shown) normally holds the armature latch 50 in engagement with the pawl 46, but when an associated magnet RCM is energized the latch is moved away from the pawl, thus connecting the shaft 38 to the driving gear 37. Shaft 38 carries a series of cams by means of which cam contacts R1, R2 are operated.

The shaft 38 is provided with an eccentric 56 (Fig. 18) for operating card feed picker slides 58. Encircling the eccentric is a strap 60 which receives a reciprocating motion for each rotation of the shaft 38. The strap 60 is formed with an ear pivotally attached to an arm 62 which also carries a pair of gear sectors 64. The sectors 64 mesh with racks 65 provided on the bottom of the picker slides 58 and form a driving connection therewith. The slides 58 carry a projecting picker knife 66 which is adapted to engage the bottom card in the hopper R. It is apparent from the above-described connections for the reproducer clutch that when the magnet RCM is energized the picker knife 66 is moved to the right, thus bringing the bottom master card 10 in the hopper R into cooperation with a pair of feeding rollers 68 and 70. Such a feeding action occurs during each cycle of operation when the machine is employed for straight reproducing.

The feeding rollers 68 and 70 are driven by a gear 72 (Fig. 17) mounted on the shaft 38 and in mesh with a gear 74 carried on the roller 68. A smaller gear 76 on the roller 68 cooperates with a similar gear 78 on the roller 70 so that both rollers are turned simultaneously but oppositely. The rollers 68 and 70 extend across the machine between the side frames 21 and the roller 68 is slotted at various column positions to permit proper placement of the master brush 14 in any desired position. These rollers, when turning, draw a card from beneath the hopper R and feed it to the left between the brushes 14 and 15 and over into other feeding rollers 80 and 82.

A contact roller 84 is associated with the brushes 15 and is driven by gear connections from the feed roller 68, the gear 76 on the roller 68 meshing with an idler gear 86 which, in turn, meshes with a gear 88 on the contact roller 84.

The punch clutch under the hopper P is operated when connections are established between the punch feed drive shaft 31 and the punch clutch driving gear 27. Attached to the gears 27 and 32 is a notched disc 90 which is loosely mounted on the shaft 31. Adjacent the disc 90 is an arm 92 fixed to the shaft 31 and carrying a clutch pawl 94 which is pivoted thereon. The pawl has an extension adapted to fit into the notch in the disc 90 and is normally urged into engagement with the disc by a suitable spring (not shown). However, the pawl is held disengaged by an armature latch 98 which engages an extending arm on the pawl. When the punch clutch magnet PCM is energized, the associated armature is attracted and the latch 98 is rocked to the left about a pivot 100, thus releasing the pawl 94 and connecting the shaft 31 to the driving gears.

When the shaft 31 is operated, certain driving connections are rendered operative to actuate a card picker mechanism under the hopper P, which is similar to the previously described card picker mechanism under the hopper R and which is generally designated by the reference character 102. Additionally, a driving connection exists between the shaft 31 and the checking station feed rollers. A third driving connection exists between the shaft 31 and operates to release a clutch connection in a Geneva gear drive whereby intermittent motion of the card is brought about as previously described. These driving connections are not fully disclosed in the accompanying drawings, but reference may be had to the patent previously mentioned for a full disclosure thereof.

A gear 104 mounted on the shaft 31 meshes with a gear 106 mounted on the same stub 34 with the gear 33. The gear 106 meshes with a gear 108 attached to a feed roller 110. Another gear 112 on the feed roller 110 meshes with a gear 114 attached to a shaft 116 which carries a series of cams by means of which the cam contacts P1, P2, P3, etc., are operated. The gear 114 meshes with a gear 118 attached to the feed roller 80 which also carries a small gear 120 in mesh with a simi-

lar gear 122 on the associated roller 82. A small gear 124 on the roller 110 drives a similar gear 126 on an associated roller 111. An idler gear 128 meshes with the gear 120 and drives a contact roller 130 through a gear 132 mounted thereon. Another idler gear 134 meshes with the gear 124 and serves to drive a pinion 136 mounted on a card deflecting eject roller 138.

A plurality of punch feeding rollers 140, 142, 144 and 146 are suitably geared and are driven from the driving gear 26 for feeding cards under the punch plungers 18. Suitable connections also extend from the gear 26 to the Geneva drive, previously referred to, for applying intermittent movement to the cards passing through the punching station. These driving connections are fully disclosed in the previously mentioned patent.

The connection just referred to for the Geneva drive mechanism includes a clutch between the Geneva gear wheel proper and the feed rollers so that feeding may be prevented when cards are not to be punched. The clutch mechanism is so designed that if the magnet PCM is not energized there is no driving connection to the Geneva wheel arrangement, and if this latter magnet is energized the usual driving connection is existent. A gear 148 meshes with two gears 150 and 152 on the feed rollers 140 and 144, respectively. An idler gear 154 between the gear 152 and another gear 156 forms the driving connections over to a feed roller 158 on which the gear 156 is mounted. A small gear 160 on the roller 140 cooperates with a similar gear 162 on the roller 142. The same sort of gear connection is made between a pair of gears 164 and 166 on the rollers 144 and 146 and between gears 168 and 170 on the roller 158 and its associated roller 159.

An idler gear 172 connects the gear 164 to a gear 174 on a contact roller 176. Another idler gear 178 meshes the gear 168 and a pinion 180 attached to a card reject roller 182. In the operation of the perforating machine, when a group of master cards 10 are placed in the hopper R, the bottom card depresses a hopper contact lever RHL closing the associated contacts RHC of Fig. 20a. Subsequently, when the picker mechanism is operated the bottom card alone is forced through the throat 184 and placed between the feed rollers 68 and 70 which feed the card along the machine.

Upon entering the sensing station, the card engages and operates a card lever RCL1. At the same time the card passes between the brush 14 and a contact plate 186. From there the card passes between the brushes 15 and the contact roller 84, and at the same time operates a card lever RCL2. Common contact brushes 188 carry the sensing current to the roller 84. The brushes 15 are arranged in a single line.

The card passes on to the feed rollers 80 and 82, which feed it between a pair of guide plates 190 and 192. A card lever CHCL is operated as the card passes between the checking brushes 16 and contact roller 130. After leaving the brushes 16, the card is engaged by the rollers 110 and 111 which serve to eject the card to the stacker 12 wherein the cards are supported on the top of a depressible spring plunger 194.

The brush 14 is adjustable along the length of the card in order that it may cooperate with any column therein.

The detail cards 11 and any master cards 10 which may be placed in the hopper P follow a course through punching and sensing stations before being deposited in the stacker 13. The cards in this hopper depress the hopper contact lever PHL and close the associated contacts PHC (Fig. 20a). Upon operation of the picker mechanism 102, the bottom card passes through a throat 195 and is placed between the feed rollers 140 and 142 which feed the card along between the brush 17 and contact bar 196. As the card passes, it operates a card lever DCL. The brush 17 is adjustable in the same manner as the brush 14. After leaving the master card

sensing station, the card is fed between a stripper plate 197 and die plate 198 and enters between the feed rollers 144 and 146, which latter rollers feed it between guide plates 199. A card lever PBCL is operated as the card passes between the sensing brushes 19 and contact rollers 176. An insulation block holds contact brushes 19 in contact with the roller 176. When the card leaves the brushes it is engaged by the rollers 158 and 159 which eject it past the deflector roller 182 into the stacker 13.

The selective operation of the punch plungers, by means of mechanism designated in its entirety at 200, is fully set forth in the previously mentioned patent and reference should be had thereto for an understanding thereof. It is deemed sufficient to state that the operation of punching is timed to occur during the pause in card feeding when the Geneva drive wheel mechanism is not in action.

Driving connections for ticket stub feed and sensing mechanisms

Referring to Fig. 1, the ticket stub feed and sensing mechanisms are shown assembled as a unit between a pair of side frame members 201 and 202. These side frame members are joined together at the bottom by a support plate 203. The support plate in turn is fastened by bolts 204 to an extension 205 of the frame of the reproducing machine, the entire assembly being located adjacent to the read hopper R of the reproducing machine.

The drive is taken from the continuously running reproducer shaft 40 by means of a timing belt 206 which is connected between a pulley 207 fastened on shaft 40 and a pulley 208 fastened on a bushing 209 which is rotatable on a shaft 210. The shaft 210 is journaled in the frame members 201, 202 and has a lock nut 211 attached at one end as shown in Fig. 2.

As shown in Fig. 3, the drive is transmitted from the pulley 208 to a driving gear 212, fastened on shaft 210, by means of a clutch mechanism. This clutch will be referred to hereinafter as the ticket clutch and, as will be seen, it must be operated before the ticket stub feeding and sensing devices can operate. The ticket clutch mechanism comprises a toothed clutch wheel 213 which is fastened to the pulley 208 and revolvable therewith on shaft 210. For cooperation with the toothed wheel there is provided a pawl 214 which is pivoted to a clutch disc 215 fixed on the shaft 210. The pawl 214 is normally held out of engagement with the toothed clutch wheel by a magnet armature 216 which is pivoted on a bracket member 217 fastened to the outside of the frame member 202. The bracket member 217 supports a ticket clutch magnet TCM and also a spring blade member 218 which serves to maintain the armature in its unattracted position where it will engage the pawl 214. The pawl 214 is biased in a clockwise direction by a compression spring 219 which is mounted in a support block 220 fastened to clutch disc 215.

Energization of the clutch magnet will release the pawl 214 for engagement with a tooth in the clutch wheel 213. When this happens the clutch disc 215, shaft 210 and gear 212 will be driven in a clockwise direction. At the end of one revolution the armature 216 will be in its unattracted position and will disengage the pawl from the clutch wheel thereby causing the shaft 210 and gear 212 to stop rotation. A detent lever 221 pivoted to the frame member 202 is biased clockwise by a spring 222 and cooperates with a notched portion 223 on the clutch disc to detent the clutch mechanism.

The gear 212 which is located on the shaft 210 adjacent the inner side of frame member 202 meshes with and drives a gear 224 fixed on a shaft 225. The shaft 225 is one of the main cam shafts and is journaled in the frame members 201 and 202. Also fastened on shaft 225 is a pulley 226 which, by means of a timing belt 227,

serves to transmit the drive from gear 224 to a pulley 228 fastened on a bushing 229 which is rotatable on a shaft 230. Thus, whenever gear 212 is rotating the drive extends also through gear 224, shaft 225, pulley 226 and pulley 228.

The shaft 230 is also a cam shaft and is mainly responsible for controlling the operation of the sensing mechanism. The shaft is controlled from a one revolution clutch mechanism which is identical to the one described for shaft 210. It will suffice to say, then, that when a sensing clutch magnet SCM on bracket 231 is energized, a pawl 232 is released by the magnet armature 232a and the spring 232b forces the pawl into engagement with a toothed clutch wheel 233 which is driven by the pulley 228 through the ratchet collars 234 (see Fig. 2). The pawl 232 is fastened to a clutch disc 235 fixed on the shaft 230 and consequently the disc and shaft will be rotated. De-energization of the magnet SCM allows a spring blade 236 to restore the armature 232a disengaging the pawl from the clutch wheel 233 and stopping the clutch disc 235 and shaft 230. A pivoted detent lever 237 biased by a spring 238 serves to detent the clutch disc 235.

Frictionally mounted on the shaft 225 is a pulley 239 and ratchet wheel 240 which is affixed to said pulley. During the normal rotation of shaft 225 the ratchet wheel 240 and pulley 239 are prevented from being rotated by the engagement of a magnet armature 241 with the ratchet wheel. The magnet armature is mounted on a bracket member 242 which supports a skid roll clutch magnet SRCM. Energization of the magnet SRCM disengages the armature 241 and the pulley and ratchet wheel assembly will rotate with shaft 225. When the magnet SRCM is de-energized, a spring blade 243 restores the armature into engagement with the ratchet wheel 240 and stops the assembly from rotating.

The pulley 239, by means of a belt 244, drives a pulley 245 fixed on a skid roll shaft 246. The belt 244 is guided by a pair of guided rollers 247, 248 rotatably mounted on brackets 249, 250 secured to the outside of frame member 202. The skid roll shaft functions to control the feeding of a ticket stub out of the feed hopper as will be described in connection with the ticket stub feed mechanism.

Ticket stub feed magazine

The magazine for holding the ticket stubs preparatory to feeding may be seen in Fig. 13 where it is shown in an inverted position, which is the position it assumes when assembled on the ticket stub feeding device.

The magazine comprises a pair of side plates 251, 252, a back plate 253 and a horizontal plate 254, all of which are fastened together to form a magazine or hopper as shown. Rigidly attached to the plate 254 and extending vertically downward is a rectangular rod 255 having a small hole 256 in its free end. The rectangular rod 255 is adapted to extend through the rectangular registration holes F in the ticket stubs when the stubs are placed in the magazine and serves to guide the stubs during the course of feeding. The bottom end of the rod 255 tapers out slightly and snugly supports the next to the bottom ticket, the remainder of the tickets being loosely guided by said rod. Cut on the inside of the two side plates 251, 252 is a groove, such as is indicated at 257, and these two grooves serve as tracks for guide pins (not shown) fastened to each end of a weight 258. The weight 258 is free to slide up and down the rod 255 and as will be later understood aids in initiating a positive feed of the bottommost ticket stub.

To load the magazine, the magazine is inverted from the position shown in Fig. 13, the weight dropping against the plate 254, and the ticket stubs are threaded on the square rod 255. The magazine is then inverted again and assembled on the ticket feeding device with the tickets in position to be taken off one at a time from the end of the square rod 255.

For mounting the magazine onto the feeding device there is provided on the outside of each of the magazine side plates a slot such as is indicated at 259 in Fig. 13 and at 260 in Fig. 1. These slots enable the magazine to be mounted on a pair of vertical guide rails, such as the one indicated at 261 in Fig. 2, and in between a pair of guide brackets 262, 263 as shown in Fig. 1. Each of said guide rails is attached to one of the guide brackets and the guide brackets are fastened to a base plate 264 of the ticket feeding device.

When the magazine is mounted in place on the feeding device, a block 265 (Fig. 13) attached to the magazine side plate 251 cams a ticket magazine interlock lever TMIL (Figs. 1 and 2) for the purpose of closing a microswitch 266. The microswitch contacts are identified hereinafter in connection with the wiring diagram as the ticket magazine interlock contacts and, as will be understood, they serve to condition the starting operation of the feeding device.

It will be noted that the ticket magazine is mounted at an angle to the expected line of travel of the ticket stubs between the side frames 201 and 202. This arrangement is in keeping with the principles of the invention for, as previously mentioned, one of the main objects of the present invention is to provide means for feeding the stubs from registration holes within the stubs themselves rather than from the sides or edges. As such the stubs in the magazine are pivoted around the bar 255, one at a time, into a position where they may be released and grasped by other feeding means for conveyance between the side frames 201, 202.

Ticket stub feed mechanisms

The ticket stub feed mechanisms make up the main substance of the present device and consist of three separate units; namely, a skid roll feeding device for offsetting the bottom ticket in the magazine, a sliding block pin feed device for conveying the tickets to the static sensing device, and an eject mechanism for ejecting the ticket from the sensing device into an eject stacker. Referring to Fig. 4, the path of feed for the ticket S is from the ticket magazine to the position indicated at S₁ where it is grasped by the sliding block pin feed device and conveyed to the position indicated at S₂ to be sensed by the sensing device. After sensing, the ticket is ejected to the position indicated at S₃ in the eject stacker.

Skid roll feed mechanism

The skid roll feeding mechanism is best shown in Figs. 4, 5 and 6. With the magazine mounted in place the pack of tags is supported by three components; namely a skid roll 267 (Fig. 4), a card lever roller 268 and a bushing 269 which is mounted in the base plate 264 as shown in Fig. 8.

Slidable within the bushing is a short rod 269a which is attached to a vertically arranged link 270 as shown in Fig. 6. Mounted in the top of the rod 269a is a diamond-shaped stud 271 which is adapted to enter the square registration hole F¹ of the bottom ticket in the magazine. The apices of the stud are positioned with respect to the sides of the registration hole F¹ about as shown in Fig. 4 and allow for free rotation of ticket as will be presently described.

On the top of the stud 271 there is fixed a pin 272 which is adapted to enter the hole 256 in the bottom of the square rod 255 when the magazine is inserted in place. The pin 272 assures that the square rod and the diamond-shaped stud are in alignment to allow the bottom ticket to fall accurately in place on the bushing 269. As seen in Fig. 8, clearance between the end of rod 255 and the top of bushing 269 is such that the stud 271 extends upward through the thickness of the bottom ticket while the rod 255 extends downward only partially through the thickness of the next to the bottom ticket. The bottom ticket may then be rotated about the stud

271 while the next to the bottom ticket is held against movement by the rod 255. The top surface of bushing 269 is kept to a minimum size so that warped tickets will lie substantially flat on said surface. Also the top of bushing 269 and skid roll 267 are above the base plate 264 to permit warped tickets to settle on these points without pressing against the base plate.

The card lever roller 268 extends up through a semi-circular opening in the base plate 264 and is mounted 10 on a spring arm 273 which is fastened to the top of a microswitch 273a to close same when ticket stubs are placed in the magazine. The microswitch 273a in turn is attached to a support bracket 274 (Fig. 5) bolted to the underside of the base plate 264. The spring arm and 15 roller are hereinafter referred to in the electrical description as the ticket magazine card lever TMCL.

Referring to Fig. 4, the skid roll 267 is fixed on the skid roll shaft 246, the shaft itself being rotatable in a support bearing bracket 275 attached to the underside 20 of the base plate 264. The skid roll projects slightly through an opening 276 in the base plate 264 bearing against the underside of the bottom ticket. Each energization of the skid roll clutch magnet SRCM will, 25 through the gear train previously described, cause the skid roll to revolve and rotate the bottom ticket around stud 271 to the position indicated at S₁. The duration of rotation of the skid roll each cycle is short and as can be seen from Fig. 21 extends for approximately two and one-half cycle points on the machine index as governed by a pin bail contact to be later described. At the completion of skid roll rotation, the ticket is located in alignment with the pin feed path of travel and partially extends underneath a guide plate 277 and extension guide member 278. The guide member 278 is a thin plate 30 having its leading edge turned up slightly and is bolted to the guide plate 277 which in turn is removably mounted on top of the base plate 264 by means of a thumb-screw 279.

After the ticket is located at position S₁, certain mechanisms are operated for lowering the diamond stud 271 clear of the registration hole F in the ticket and at the same time raising the remaining pack of tickets in the magazine preparatory to the operation of the pin feeding device. These mechanisms may best be seen by referring to Fig. 6.

The link 270 for the diamond stud is shown pivoted at 280 in a slot in one end of a bar 281. The bar 281 is in turn pivoted at 282 to the support bracket 274 (Fig. 5) and supports an adjustable stop screw 283 the function of which will be presently described. Directly underneath the bar 281 and in alignment therewith is a follower arm 284 which is pivoted on a stud 285 fastened to the inside of side frame 201. Arm 284 has a roller follower 286 which rides on the periphery of a cam 287 fixed on the cam shaft 225. The arm 284 is normally urged in a counterclockwise direction about stud 285 by a spring 288 fastened between said arm and a stud (not shown) which is attached to the side frame 201. Normally a predetermined space relationship is maintained between the stop screw 283 and the follower arm 284 by means of a spring 289 fastened between the studs 290 and 291. As best seen in Fig. 5, there is attached to the follower arm 284 a lift bail 292 which extends upward vertically, the upper end 60 normally coming approximately flush with the ticket feed bed.

As the ticket is located in position S₁ the high portion on cam 287 will come into position to cam the follower arm 284 clockwise driving the lift bail 292 up through an opening 293 in the base plate 264 a slight distance sufficient to raise the pack of tickets remaining in the magazine, particularly at the ends which contain the registration hole F as shown in Fig. 4. As the follower arm pivots clockwise to raise the lift bail, it strikes 70 the bottom of stop screw 283 causing the bar 281 to

pivot clockwise a sufficient amount to pull the link 270 downward until the diamond stud 271 and pin 272 are clear of the ticket feed bed. The ticket in position S_1 is now free to be carried to the sensing station by the pin feed device.

Extending vertically upward through the opening 293 and parallel with the lift bail 292 is a gripper arm 294 having an elongated hole near the bottom which is mounted on a stud 295. The stud 295 is fixed to a support bracket 296 (Fig. 5) which is fastened to the inside of side frame 201. In the normal position, the gripper arm is maintained at the upper limit of its travel with the stud 295 seated in the bottom of the elongated slot by means of a spring 297 fastened between the end of the arm and a stud on bracket 296. The upper end of the gripper arm has a toothed nose portion 298 which is adapted to swing into engagement with the bottom few cards in the magazine each cycle, as will be presently described to aid in positively seating the bottommost ticket onto the diamond-shaped stud 271 preparatory to feeding another ticket out of the magazine.

As shown in Fig. 5, the gripper arm normally bears against an ear 299 formed on the lift bail 292 due to the influence of spring 297 and in this position the toothed nose 298 is clear of the tickets in the magazine. Also, formed in the gripper arm is a notched portion 300 through which extends a cam arm 301. The cam arm 301 has a block portion 302 which is fastened to an auxiliary shaft 303. The auxiliary shaft 303 is journaled in a pair of support brackets 304, 305 which are fastened to the underside of the base plate 264. Also, fixed on the shaft 303 is a cam lever 306, which operates the pin feed device in a manner to be described, and a trip lever 307 which serves to operate the shaft 303 and cam lever 306.

Referring to Figs. 4 and 7, there is shown attached to the top of base plate 264 a support bushing 308 which rotatably supports a short shaft 309. Fastened to one end of the short shaft is a latch lever 310 having a hook nose portion which normally engages the end of trip lever 307 due to the influence of a spring 311 extending between an ear 312 formed on the latch lever and a bracket member 313.

Fastened on the other end of the short shaft 309 is a card lever 314 which normally is urged by spring 311 to extend down into a dip 315 formed in the top of the base plate 264. Although not shown, it should be pointed out that when the trip lever 307 is normally latched up as shown in Fig. 7, the shaft 303 is positioned so that a cam roller 316 rotatable on a follower arm 317 fixed to shaft 303 (Fig. 6) is raised slightly off from the periphery of a cam 318 fastened on the cam shaft 225. It will be understood that when a ticket is rotated out of the magazine to the position S_1 that the card lever and latch lever will be pivoted counterclockwise releasing the trip lever 307. A spring 319 fastened between the trip lever and a stud 320 will then cause the trip lever and shaft 303 to pivot clockwise a slight amount until the cam roller 316 strikes the periphery of cam 318. When latch lever 310 is unlatched it is maintained in a position for relatching at the end of an operating cycle by an ear 321, formed thereon, striking against the top of a stop screw 322 mounted on the base plate 264. At the end of the cycle cam 318 will cause the shaft 303 and trip lever 307 to return to their latched position.

The trip lever mechanism just described for the most part conditions the operation of the pin feed device; however, it also aids in the operation of the gripper arm 294. When shaft 303 was rotated clockwise the cam arm 301 was raised a slight amount to the position shown in Fig. 5, in which position it is ready to perform its function of camming the gripper arm. It will be remembered that the gripper arm normally bears against the ear 299 on the lift bail 292. When the lift bail

is moved upward to lift the tickets in the magazine, the ear 299 clears the raised portion 323 and spring 297 causes the gripper arm to pivot counterclockwise slightly until the toothed nose 298 comes into engagement with the edges of the bottom few tickets being held up in the magazine by the lift bail. After the bottom ticket has been fed out of the magazine the lift bail 292 starts its downward travel at which time the ear 299 will engage the upper edge of the raised portion 323 and force the gripper arm to move straight down with the bail. As a result the toothed portion 298 will positively force the bottom few tickets downward to insure that the bottom-most ticket will seat onto the diamond stud 271. After sufficient downward travel to accomplish the above, the upper inclined surface of notch 300 will strike the cam arm 301 causing the gripper arm to be pivoted clockwise about the stud 295. The toothed portion 298 will move out of engagement with the tickets and when the raised portion 323 clears the ear 299, spring 297 will cause the gripper arm to snap upward back to its normal position.

Sliding block pin feed mechanism

The sliding block pin feed mechanism which is utilized to convey the ticket from the position S_1 to the position S_2 beneath the sensing device is best shown in Figs. 9, 10 and 11. The mechanism is cam operated to reciprocate back and forth within two pairs of rail members 324 (Fig. 11) which are fastened to the underside of base plate 264. Each pair of rail members straddles an elongated opening 325 in the base plate through which the feed pins 326 operate.

Slidably mounted on the rail members and extending up within the elongated openings are a pair of slide block assemblies each one of which consists of two blocks 327, 328 and a spacer block 329 arranged as shown in Fig. 9. Both assemblies are bolted to the top of an operating member 330 having downwardly extending sides formed thereon for connection with the cam operating mechanism.

Fastened to the underside of the operating member 330 (Fig. 11) is a spacer 331 and then a plate 332 the front portion of which is formed with downwardly extending sides having horizontal flanges 333 at their ends. Mounted in between the operating member 330 and the plate 332 is a slide plate 334 having two downwardly extending ears 335 and a downwardly extending center flange portion 336. The slide plate contains four roller balls 337 which rest on the top of plate 332 permitting the slide plate to be moved horizontally between the operating member 330 and the plate 332.

The assembly of elements just described is provided to serve two purposes. It contains means for raising and lowering the two feed pins 326 into and out of the registration holes F^1 in the tickets and it functions as a reciprocating carriage unit for carrying the tickets from position S_1 to position S_2 on the base plate 264. The feed pins 326 (Fig. 11) slidably extend through the entire assembly and each pin has a collar 338 which bears against the underside of operating member 330 when the pins are in the raised position. Coil springs 339 retained between each pin collar 338 and the flanged ends 333 of plate 332 normally try to move the pins to their raised position. The pins are shown in their raised position in Figs. 9, 10 and 11. However, the pins are lowered at the end of each cycle, by a mechanism to be described, and are in their lowered position at the beginning of each cycle when a ticket is rotated to position S_1 .

When in the lower position, the pins are retained there by the narrow portion of the irregular slots 340 (Fig. 10) through which they extend in the slide plate 334, said narrow portion of the slots bearing against the pin collars 338 under the influence of the springs 341 (Fig. 9) fastened between the plate 332 and the ears 335 of slide plate 334. It will be remembered that when a

ticket is rotated out of the magazine to the position S_1 the card lever 314 is operated and shaft 303 is rotated slightly clockwise. The skid roll 267 stops the ticket in position S_1 with the registration holes F^1 in alignment with the lowered feed pins 326 and the subsequent rotation of shaft 303 permits the cam lever 306 (Fig. 9) to strike the flange 336 and move the slide plate 334 a sufficient amount to free the pins 326 from the narrow portion of the slots 340. The springs 339 will then drive the feed pins up through the registration holes in the ticket, the pins then assuming their raised position.

With a ticket placed on the raised feed pins in position S_1 , the carriage unit is ready to be operated to convey the ticket to position S_2 beneath the sensing device. This is accomplished by the cam mechanism shown in Fig. 9. The mechanism comprises a cam 342 fixed on the main cam shaft 225 which coacts with a roller follower 343 mounted on a follower arm 344. The follower arm 344 is fixed at one end to an auxiliary shaft 345 journaled in the side frame 201 and is normally urged in a clockwise direction under the influence of a spring 346 fastened between a stud 347 on the arm and a stud 348 attached to the side frame.

The upper end of the follower arm 344 is fixed to a rod 349 which extends through a pair of connecting links 350 (see also Fig. 6). The connecting links are in turn connected to the sides of the operating member 330 and it can be seen that as cam 342 revolves counterclockwise the follower arm will pivot clockwise and pull the entire feed pin assembly to the right or toward the rear of the machine.

As shown in Fig. 5, the pin feed assembly has reached the limit of its rearward travel and is in the middle of a short dwell period caused by the small bump on the periphery of cam 342. It will be noted that in this position the lower portion of the feed pins are positioned within the forked members 351 fastened to a pair of arms 352, 353 as shown in Fig. 6. The arms 352, 353 are fixed on an auxiliary shaft 354 journaled between the side frame 201 and a support bracket 355 (Figs. 5 and 9) fastened to the underside of the base plate 264. The lower end of arm 352 supports a roller follower 356 which rides on the periphery of a cam 357, fastened on the cam shaft 225, under the influence of a spring 358 fastened between a stud 359 on the arm and a stud 360 on the machine frame.

When the pin feed carriage unit is in its short dwell period the cam 357 will be in position to cause the arm 252 and shaft 354 to pivot counterclockwise. As a result the forked members 351 will strike the lower collars 361 on the feed pins and pull the feed pins down out of the registration holes in the ticket. As was previously mentioned the pins are retained in their lower position by the narrow portion of the irregular slots 340 in the slide plate 334 bearing against the pin collars 338 under the influence of springs 341.

As the small bump on cam 342 moves past the roller follower 343 the cam begins to force the follower arm 344 counterclockwise and the carriage unit with the feed pins retained in their lower position starts to slide back to its normal position near the front of the machine preparatory to receiving the next ticket. Also, cam 357 moves into position to allow the arm 352 and shaft 354 to rotate clockwise thereby moving the forked members 351 back up to their original position in readiness to again intercept the feed pins 326 on the next feed cycle.

When the carriage unit nears the limit of its forward travel cam 318 becomes effective to force the follower arm 317 and cam lever 306 counterclockwise. The cam lever 306 is moved back a sufficient amount to be released by the latch lever 310, in which position it is clear of the forward travel of the slide plate 332 and flange 333 and cannot prematurely effect the release of the feed pins.

Referring to Fig. 9, it will be noted that there is a

microswitch 362 mounted on a bracket 363 which is fastened to the frame member 202. The microswitch is hereinafter referred to in the electrical description as the pin bail contact and is normally held closed by the bottom color 361 of the feed pin when the carriage unit is at its forward limit of travel. The contact is opened by the release of the feed pins and remains open during the travel of the carriage unit.

When in the position S_2 , the ticket rests partially beneath a pressure pad 364 (Fig. 4) and an upper guide plate 365. The pressure pad 364 is a part of the sensing device which is to be described later. The guide plate 365 is positioned in place by a pair of screw studs 366 arranged on the top surface of base plate 264 and a thumb screw 367 which screws into the side of the frame member 201. The thumb screw 367 is provided so that the guide plate may be conveniently removed if desired.

Referring to Figs. 1 and 4, the arrival of a ticket into position S_2 cams a sensing card lever SCL, which is pivoted in a bracket 368 fastened to the top of base plate 264, clockwise to close a pair of contacts TSC fastened to the underside of the base plate. The closure of contacts TSC controls the readout of the sensed information in a manner to be described. Referring to Figs. 1 and 2, there is shown a pair of contacts T_1 and T_2 mounted on a bracket 369 which is fastened to the support plate 203. The contacts T_1 and T_2 are operated by a pair of cams 370 and 371 fastened on the shaft 210.

Eject feed mechanism

As was previously mentioned, after sensing, the ticket is fed from position S_2 to the position S_3 in the eject stacker. The mechanism for initiating the eject feed comprises a face cam 372 (Fig. 6) integral with the gear 224 on shaft 225. Cooperating with the face cam is a follower arm 373 pivoted on a bracket 374 which is fastened to the frame member 202. A roller follower 375 rotatably mounted on the end of the follower arm rides against the face cam under the influence of a spring 376 fastened between a stud 377 on the follower arm and a stud (not shown) on frame member 202.

The upper end of the follower arm has a bent flange portion 378 which projects slightly up through a slot in a pusher plate 379. The follower arm and flange extend through an opening in the base plate 264 with the bottom surface of the pusher plate coming flush with the top surface of the base plate. A guide plate 380 (Fig. 4) fastened to the base plate extends around the pusher plate and is provided with an opening 381 to allow for the movement of the follower arm 373 and flange 378. When in the position S_2 the ticket is in alignment with the pusher plate and it can be seen that when the roller follower 375 enters the depression in the face cam near the end of the cycle the follower arm will pivot clockwise causing the raised leading edges 382 of the pusher plate to engage the ticket and push it out from position S_2 and toward position S_3 .

The pusher plate kicks the ticket in between a pair of eject feed rollers 383 and 384 (Figs. 4 and 5). The top feed roller 383 is rotatably mounted in a U-shaped block 385 which is pivoted on a stud 386 fastened to a support block 387. A spacer 388 separates the block 385 from the support block 387. A spring 389 extending between the blocks 385 and 387 urges block 385 to pivot about stud 386 to maintain the feed roller 383 against the feed roller 384.

The feed roller 384 is fixed on a short shaft 390 (Figs. 5 and 6) which is rotatable in a bearing block 391 fastened to the underside of the base plate 264. The feed roller 384 is driven by means of a pulley 392 fixed on the end of shaft 390, a pulley 393 fixed on the main cam shaft 225 and a belt 394 which connects said two pulleys. The belt 394 is guided from the pulley 393 onto pulley 392 by a small pulley 395 rotatably mounted on a bracket 396 (Fig. 5) which is fastened to

the inside of frame member 202. The revolving feed rollers 383, 384 accept the ticket from the pusher plate and feed it onto a stacker plate 397 (Figs. 1 and 4). The ticket will be stopped by a vertical ear 398 formed on a guide bracket 399 fastened to the frame member 201. The guide bracket supports a vertical rod 400 upon which is slidably mounted a bushing 401 fastened to the top surface of the stacker plate 397. An ear 402 formed in the stacker plate fits loosely into a vertical slot 403 cut in the frame member 201 and the stacker plate is free to move up and down along the slot and the vertical rod. The stacker plate is biased upward by a spring 404 fastened between the stacker plate and a bracket arm 405 mounted on top of the sensing unit. As the tickets accumulate on the stacker plate, the plate gradually descends until it reaches the bottom of its travel where it closes a microswitch 406, hereinafter referred to as the ticket stacker switch, to signal that the stacker is filled to capacity. A guide plate 407 is provided along the left side of the stacker mechanism and is fastened to the frame member 301.

Sensing unit

The sensing unit, which is best shown in Figs. 2, 5 and 12, senses the ticket while the pin feed carriage unit is at rest with the ticket located in position S_2 . It comprises a series of twenty-five groups of five wire bundles each arranged across the width of the unit. Each wire bundle 408 (Fig. 12) actually consists of five individual sensing wires, there being a wire bundle for each index point position on the ticket.

The wire bundles are frictionally threaded through rows of slits formed in a series of five wire carrier strips 409. The wire carriers are arranged in layer form and assembled to a cross plate 410 which forms the front cross member of a U-shaped sensing carriage 411. The means for assembling the wire carriers comprises eight narrow brass spacer strips 412 interleaved between the carrier strips, there being four spacers extending from top to bottom along each side of the assembly. Four bolts 413 along with eight insulating blocks 414, one placed at each corner of the assembly, and four insulating sleeves 415 are provided for holding the assembly together. The bolts 413 also serve to fasten a support plate 416 to the front of cross plate 410. Projecting from each corner of the support plate 416 is a rounded flange 417. The flanges slidably support a pair of posts 418 which are fixed to the nylon pressure pad 364. The posts 418 are biased by a pair of springs 420 extending between the upper two flanges 417 and collars 421 formed on the posts.

It will be noted that the upper two bolts 413 also extend through an insulating block 422 fastened between the upper two flanges 417. The top surface of block 422 extends slightly above the top surface of the assembly and supports a block 423 having three comb plates 424 arranged across the top of the assembly. The comb plates 424 each have five notches which serve to position the upper ends of the wire carrier strips.

The sensing carriage 411 is adapted to be reciprocated up and down by two pairs of complementary cams 425 and 426 fastened on the shaft 230. The carriage is supported by means of two upper roller followers 427 pivoted to the outside of the carriage frame which ride on the cams 425 and two lower roller followers 428 pivoted to the inside of the carriage frame which bear against the periphery of cams 426. A pair of guide strips 429 are fastened to the top and bottom of a support casting 430 which is bolted to the side frame 202. The guide strips 429 are slotted at the ends to receive the upper guide rollers 431 and lower guide rollers 432 rotatably mounted to the inside of the carriage frame and serve to guide the movement of the carriage.

In Fig. 12, the sensing carriage is shown at the bottom of its travel with the pressure pad 364 down against the

ticket and two of the sensing wires extending through holes in the ticket. The pressure pad serves to keep the sensing wires in direct alignment with the hole positions on the ticket to insure accurate sensing. At the start of 5 the downward movement both the carriage and the pressure pad move downward due to springs 420. When the pressure pad is stopped by the ticket and base plate 264 the carriage continues to descend against the force of springs 420 a sufficient distance to allow the sensing wires to enter the holes in the ticket.

After sensing the perforations, the sensing wires are 15 raised just enough to clear the ticket after which a dwell in the cams causes the sensing wires to stop and remain in the setup position shown in Fig. 12 until the information they represent is entered into a suitable storage device to effect subsequent punching of the card. The mechanism for effecting storage of the sensed data comprises a 20 nylon terminal block 433 fastened to the front of the support casting 430. The terminal block carries a series of terminal wires 434, one for each sensing wire, which are parallel with the sensing wires and offset toward the front of the machine. The terminal wires 434 project slightly from the underside of the terminal block and each wire is positioned adjacent one of a plurality of notches 435 formed in the underside of the terminal block. The 25 sensing wires 408 normally have their upper ends positioned within the notches 435. It can be seen in Fig. 12 that the wires that were not displaced by holes in the ticket still have their upper ends positioned within the notches whereas the wires that sensed holes in the ticket were carried downward a sufficient distance to be clear of the notches. The terminal wires are electrically connected, as will be later shown, to suitable storage means and the sensed data is entered into storage by camming 30 the displaced sensing wires into contact with the adjacent 35 terminal wires.

The mechanism for camming the displaced sensing wires comprises a second U-shaped carriage 436 having four rollers 437 rotatably mounted thereon and supported 40 within the notched ends of a pair of support members 438 fastened to the inside of the side walls of the casting 430, as shown in Fig. 2. Two pairs of complementary cams 439 and 440 fastened on shaft 230 cooperate with two sets of roller followers 441 and 442 rotatable on the carriage unit to cause the carriage 436 to reciprocate horizontally on the support members 438.

Fastened to the front cross member 443 of the carriage is an insulating block 444. The bottom side of the insulating block extends below the cross member 443 and has attached thereto a bail 445. The bail 445 is U-shaped having two arms 446 which fit loosely into the U-shaped portion of a nylon guide block 447 fastened to the terminal block 433. Fastened between the bail arms 446 and 50 extending across the width of the assembly is a series of six rods 448 positioned so that there is a rod extending alongside each of the five rows of twenty-five sensing wires.

After sensing, carriage 411 is moved upward to an intermediate position (not shown) and cams 439 and 440 55 move the carriage 436 toward the left or front of the machine thereby causing the rods 448 to cam the displaced sensing wires into contact with the terminal wires and completing circuits for entering the sensed data into the storage device. Subsequently cams 439 and 440 cause 60 the carriage 436 to return back to its normal position after which the cams 425 and 426 continue the return of carriage 411 and pressure pad 364 upward to their normal position. The upward movement of the carriage 411 carries all of the sensing wires upward also, restoring 65 them to their normal position in the notches 435.

Referring to Figs. 1 and 2, there is shown a cam 449 70 fixed on shaft 230 which operates a pair of normally open contacts S_1 mounted on a bracket 450 fastened to the side of the main casting 430. Contacts S_1 serve to con-

trol the operation of the sensing device in a manner to be presently described.

Electrical connections

The electrical connections between the devices of the machine may be studied by reference to the wiring diagram shown in Figs. 20a to 20c. The present description will be concerned with the use of the machine for reproducing operations wherein only the punch section of the machine is used, the novel ticket feeding and sensing devices operating in place of the read section of the machine.

First cycle

Referring to Fig. 20a, when the main switch is closed 110 volts A.C. is applied across the transformer T and rectifier R to provide a source of 40 volts D.C. across the two main lines 451 and 452 of the machine. Blank cards are inserted in the punch feed hopper P and the ticket stubs are placed in the ticket magazine. The cards in the hopper P operate the card lever PHL, closing contacts PHC, and energizing relay R3 by a circuit which extends from line 451, wire 453, contacts PHC, relay R3, wire 454 and line 452. The tickets in the magazine operate card lever TMCL, closing contacts TMC, and energizing relay R6 by a circuit which extends from line 451, the ticket switch in the closed position, wire 455, contacts TMC, relay R6, wire 454 and line 452. Now the start key is depressed to complete a circuit from line 451, wire 456, the normally closed stop switch, the start switch in the closed position, transferred contacts R6-2, transferred contacts R3-2, the closed ticket magazine interlock contacts, relay R10 and line 452. Relay R10 holds through a circuit which extends from line 451, wire 457, cam contacts P6, transferred contacts R10-2, relay R10 and line 452. The energization of relay R10 completes a circuit from line 451, wire 453, transferred contacts R10-5, motor relay RHD1 and line 452. A parallel circuit is also completed from the transferred R10-6 contacts, relay R9 and wire 452.

The energization of the motor relay RHD1 closes contacts RHD1-1 and operates motor M through the 110 volt lines 458 and 459. Circuits are now completed to energize the punch clutch magnet PCM and the ticket clutch magnet TCM. The circuit to the punch clutch magnet extends from line 451, wire 460, transferred contacts R9-4, transferred contacts R10-3, normally closed side of contacts R1-1, wire 461, cam contacts C1, the punch clutch magnet PCM and line 452. With the ticket switch closed a circuit is maintained which extends from line 451, the ticket switch, wire 462, relay R26 and line 452. As a result the circuit to the ticket clutch magnet now extends from line 451, wire 460, transferred contacts R9-4, transferred contacts R10-3, the normally closed side of contacts R4-1, wire 463, cam contacts C2, transferred contacts R26-1, closed contacts R6-5, the ticket clutch magnet TCM and line 452. The ticket clutch magnet TCM is energized at 14.0 of the first cycle and at 14.1, cam contacts T₁ close to complete a circuit from line 451, the closed ticket switch, wire 462, cam contacts T₁, the normally closed pin bail contact, the skid roll clutch magnet SRCM and line 452.

With the punch clutch, ticket clutch and skid roll clutch magnets all energized at about the same time in the beginning of the first cycle, the first blank card in the punch hopper is fed out of the hopper toward the punching station and the bottom ticket stub is rotated out of the ticket magazine into position S₁. Upon entering position S₁, the ticket stub operates the card lever 134 releasing the feed pins 326 and the pin feed slide assembly goes into operation as previously described to carry the ticket stub to the sensing position S₂. It will be remembered that as the ticket is positioned on the feed pins, the normally closed pin bail contacts (microswitch 362 on Fig. 9) are opened disabling the circuit to the skid

roll clutch magnet at 11.3 in the cycle. As a result, skid roll rotation is stopped until it is time to feed another ticket stub out of the magazine in the next cycle.

At 11.5 time in the cycle the cam contacts T₂ close 5 to complete a circuit from line 451, the closed ticket switch, wire 462, wire 464, cam contacts T₂, the sensing clutch magnet SCM and line 452. Energization of the magnet SCM effects the operation of shaft 230 and the sensing unit operating cams mounted therein. Also, the entry of the ticket stub into the sensing position S₂ 10 operates the sensing card lever to close the ticket sensing contacts TSC. Closure of contacts TSC at 3.0 time in the cycle completes a circuit from line 451, the closed ticket switch, wire 455, contacts TSC, closed contacts R26-2, relay R4, wire 454 and line 452. Relay R4 holds 15 through a circuit which extends from line 451, the closed ticket switch, wire 455, closed contacts R4-6, cam contacts P11, closed contacts R26-2, relay R4, wire 454 and line 452. Relay R4 is held over into the next cycle to 20 allow the normally open side of contacts R4-1 to operate the punch clutch magnet.

From 4.3 to 4.6 time in the cycle the sensing carriage 411 is at the bottom of its travel and the sensing wires 25 are being displaced in accordance with the perforations in the ticket stub. At 4.6 time they are raised a sufficient distance to clear the ticket, at the same time remaining in their setup position. At 5.6 time the horizontally reciprocating carriage 436 operates to cam the displaced sensing wires 408 against the terminal wires 434 and 30 these wires are maintained in contact until 0.8 time of the next cycle.

The sensed information is retained in this setup condition until cam contacts P12 close at 9.7 time near the 35 end of the first cycle. Closure of cam contacts P12 completes circuits for entering the sensed information into storage relays where it is retained until punching time in the second cycle. These circuits extend from line 451, the closed ticket switch, wire 455, closed contacts R4-6, wire 465, cam contacts P12 (Fig. 20b), cam 40 contacts S₁, common wire carrier strip 409, sensing wires 408 that were displaced, terminal wires 434, code storage relays R101 through R222 and line 452. Referring to Fig. 19, the relationship between the code storage relays and the code positions on the tickets is shown for the 45 first 24 columns of punched information. The 25th column being always punched in either or both of the positions shown in Fig. 16, for control purposes only, are provided with code relays R221 and R222. The code storage relays are held until 9.2 time near the end of the second cycle by circuits which extend from line 451 (Fig. 20b), cam contacts P2, the closed number 1 points of the storage relays, the hold coils of the storage relays, wire 466 and line 452.

Near the end of the first cycle the eject mechanism 55 operates to eject the ticket stub from position S₂ to the position S₃ in the eject stacker. Also, at the end of the first cycle the first blank card in the punch is positioned at the die card lever DCL and is just ready to enter under the punches for punching. The closure of the die card 60 lever DCL completes a circuit from line 451 (Fig. 20a), wire 453, DCLC contacts, relay R1, wire 454 and line 452. With relay R1 energized, the normally open side of contacts R1-1 controls the energization of the ticket clutch magnet TCM on subsequent cycles.

Second cycle

During the first half of the second cycle the next ticket stub is fed into the sensing position S₂ and the second blank card in the punch is started on its way toward the die card lever station. Also, at 0.8 time in the cycle the carriage 436 moves the sensing wires away from the terminal wires after which the sensing carriage restores the sensing wires upward to reset them preparatory for another sensing operation. During the remainder of the 70 second cycle the ticket stub is sensed, the information set 75

up and the ticket ejected in the manner previously described.

Also, during the second cycle the stored information relating to the first ticket stub is read out and punched in the first blank card. It is desired to punch the information into the blank cards in the form of the standard IBM twelve hole code and as a result the sensed 2 out of 5 code is converted to the twelve hole code during readout. Referring to Fig. 20c, the circuitry for accomplishing this is shown for column one, it being understood that similar circuitry is employed for each of the columns two through twenty-four using the respective code relays assigned to each column.

Beginning at 12 time in each cycle a pulse is emitted for each of the 12 through 9 index point or punching positions on the card under the control of cam contacts C11. The circuit extends from line 451 (Fig. 20b), wire 467, cam contacts P1, cam contacts C11, wire 468, closed contacts R26-3 and R26-4 (Fig. 20c), wire 469, to the punching machine emitter EM. Assuming that the "0" in column 1 of the ticket stub, indicated by the perforations at the 7 and 4 code positions, has been sensed and is to be reproduced in column 1 in the blank record card, it will be understood that code relays R103 and R104 will be energized. Then, at "0" time in the second cycle the above circuit will be completed from the "0" spot on the machine emitter EM, wire 470, transferred contacts R103-3, transferred contacts R104-2, normally closed side of contacts R102-5, transferred contacts R103-5, normally closed side of contacts R105-3, transferred contacts R104-3, normally closed side of contacts R101-5, readout plug hub 471 for column 1, a suitable plug wire connection (not shown) to the punch normal hub 472 (Fig. 20b), normally closed side of the relay R38 contacts, punch magnet PM and line 452 to punch a "0" in column 1 of the record card. All of the stored readings for columns 1 through 24 of the ticket stub are converted and read out in similar fashion to effect punching of the record card. At the end of the second cycle after punching is completed the record card just punched will be positioned at the entrance to the punch brushes and the second record card will be at the die card lever station ready to be punched in the next cycle. With a card at the punch brushes the punch brush card lever PBCL will now be closed to complete a circuit from line 451 (Fig. 20a), wire 453, punch brush contacts PBC, relay R7, wire 454 and line 452.

Energization of relay R7 closes contacts R7-1 in a hold circuit for relay R10 which extends from line 451 (Fig. 20a), wire 456, normally closed stop switch, punch stacker switch and ticket stacker switch, closed contacts R6-3, closed contacts R7-1, closed contacts R1-2, closed contacts R3-3, closed contacts R10-1, relay R10 and line 452. With relay R10 maintained energized through the above hold circuit, the machine will continue to operate until one of the magazines runs out of cards, one of the stacker switches is opened or a record card fails to feed.

Referring to Fig. 21, it will be noted that the ticket magazine card lever relay R6 dropped out at 12 time in the second cycle. This is an indication that there were only two ticket stubs placed in the ticket magazine. As a result the ticket clutch, skid roll clutch and sensing clutch are not operated in the third cycle; however storage readout and punching take place for the second ticket stub.

Referring to Fig. 20b, it will be seen that the code relays R221 and R222 have been provided for control punchings representing R and X which may be placed in column 25 of the ticket stub. If an R hole is sensed in column 25 relay R221 will be energized and held in the same fashion as the other code storage relays and if an X hole is sensed relay R222 will become energized. Energization of relay R221 makes a pulse available at plug hub R (Fig. 20a) by a circuit which extends from line 75

451, cam contacts P3, normally closed side of contacts R222-3, transferred contacts R221-4 and plug hub R. In similar fashion energization of relay R222 or energization of both relays R221 and R222 will provide pulses at plug hubs X or RX.

The control punchings are utilized where it is desired to punch additional information on the record cards in addition to what is being reproduced from the ticket stubs. For such an operation a master ticket is usually prepared having the additional information along with an X or R control punching in column 25. The master ticket is run through the machine ahead of the ticket stubs to be reproduced and the additional information is punched into a blank master record card. Subsequent operation of the machine is on a combined reproducing and gang punching operation whereby the record card at the punch brushes effects the punching of the additional information into the following record card at the punching station while the ticket reproducing operation is being carried out.

Referring to Fig. 20b and assuming that the master ticket has an "R" punched in column 25 the code storage relay R221 will be energized and an impulse will be made available at the R plug hub in the manner previously described. The R plug hub is plug wired to a punch transfer hub 473 to complete the R impulse circuit to relay R38 and line 452. Relay R38 is held throughout the punching portion of the next cycle by a circuit which extends from line 451, wire 467, cam contacts P1, wire 474, closed contacts R38-5, the hold coil of relay R38 and line 452. The additional information in the master ticket is sensed, stored and read out in the manner previously described. The R hole completes a circuit at 12 time from the "12" spot on the machine emitter EM, closed contacts R221-2 and readout plug hub 475 for column 25.

It is well known that the standard IBM reproducing punch contains 80 punch magnets for punching into the 80 columns of the standard card and it can be understood that the 25 readout hubs can be split plug wired to the punch normal hubs 472 of the punch magnets for columns 1 through 25 and also to the punch magnet transfer hubs 476 of the punch magnets for columns 55 through 80. Consequently, the closure of the relay R38 contacts (such as R38-1 through R38-4) will direct the readout pulses for the master ticket to punch the additional information into columns 55 through 80 of the master record card, the R38 contacts serving to break the circuits from the punch normal hubs so that the master ticket information will not also be punched in columns 1 through 25.

In the next cycle the punched master card will be at the punch brush station ready to commence gang punching the information into columns 55 through 80 of the following record card at the punch station as the next ticket is reproduced into columns 1 through 25. The gang punching circuit extends from line 451 (Fig. 20a), wire 467, cam contacts P1, cam contacts C11, wire 468, closed contacts R7-3 and R7-4, common brush 477, contact roll 478, perforations in the master record card, punch brushes 19, plug hubs 479, plug wire connections to the punch normal hubs 472, punch magnets PM and line 452. At the same time the reproducing operation is being carried out as previously described.

While there have been shown and described and pointed out the fundamental novel features of the invention as applied to a preferred embodiment, it will be understood that various omissions and substitutions and changes in the form and details of the device illustrated and its operation may be made by those skilled in the art, without departing from the spirit of the invention. It is the intention, therefore, to be limited only as indicated by the scope of the following claims.

What is claimed is:

1. A cyclically operable machine of the class described

comprising ticket feeding means, record card feeding means, a sensing mechanism comprising individual wires movable from a home position to a displaced position for sensing perforated data on said ticket, perforating means for perforating said record card, a ticket stacker, means for operating said ticket feeding means to present a ticket to said sensing mechanism and then feed said ticket on into said stacker during the first cycle of machine operation, cyclically operable means for operating said sensing mechanism to effect a displacement of individual wires in accordance with the perforated data on said ticket, means for retaining said wires in said displaced condition, relay storage means, means operable subsequently in said first cycle for entering the data represented by the displacement of said wires into said storage means, means for operating said record card feeding means so as to advance a card to said perforating means in synchronism with the storage of data from a ticket by said storage means, means for causing a second cycle of operation of said machine, said record card feeding means being operable during said second cycle to feed said record card past said perforating means and said ticket feeding means being operable to feed a second ticket to said sensing mechanism, means operable during the first portion of said second cycle for restoring said wires to the home position, said sensing mechanism being operable during the second portion of said second cycle to

20

25

sense said second ticket, and readout means operable during the second portion of said second cycle for operating said perforating means to perforate said record card in accordance with the data entered into said storage means from said first ticket.

5 2. A machine as in claim 1 wherein said retaining means includes reciprocating carriage means operable after a sensing operation to move the individual wires just clear of the ticket to allow said ticket freedom of movement for said stacking operation in the first machine cycle which occurs before said wires are restored to the home position.

10 3. A machine as in claim 1 wherein the perforated data sensed on said ticket is arranged in 2 out of 5 hole code form, said relay storage means being arranged to store the sensed information in 2 out of 5 code form, and said readout means includes an emitter for converting said 2 out of 5 code and operating said perforating means to perforate said record in accordance with a 12 hole code.
